BY

Frank A. Pecklin
his ATTORNEY

UNITED STATES PATENT OFFICE.

BYERS W. KADEL, OF BALTIMORE, MARYLAND, ASSIGNOR, BY MESNE ASSIGNMENTS,
TO THE SYMINGTON COMPANY, A CORPORATION OF MARYLAND.

DRAFT RIGGING.

Application filed April 5, 1922. Serial No. 549,840.

To all whom it may concern:

Be it known that I, BYERS W. KADEL, a citizen of the United States, residing at Baltimore, in the State of Maryland, have 5 invented certain new and useful Improvements in Draft Rigging; and I do hereby declare the following to be a full, clear, and exact description of the invention, such as will enable others skilled in the art to which 10 it appertains to make and use the same.

The invention relates to draft rigging for railway cars and more particularly to improvements in friction mechanism primarily designed as the cushioning element of draft 15 rigging.

The principal object of my invention, generally considered, is to provide a friction mechanism having a separable friction collar or box and a spring housing or barrel 20 coacting therewith, the friction box being formed from a billet by a forging or pressing process, said box being of rectangular cross section and provided with shoulders 25 against which the end of the friction barrel or housing is adapted to seat.

Another object of the invention is to provide a spring barrel or housing rectangular in outline and having an integral rear end, the normal open end of the barrel being 30 adapted for the reception of portions of a friction box or casing.

Another object of the invention is to provide in the type of construction hereinbefore set forth, a spring housing rectangular 35 in outline, the end walls of which are thicker in cross section than the side walls, the said end walls converging toward the closed end of the housing.

A still further object of the invention is 40 to provide a friction box with projecting members adapted to fit within the open end of a spring housing or barrel, said projections being adapted to center the friction box with reference to the longitudinal axis 45 of the housing.

Another object of the invention is to provide in combination with a cast friction box having oppositely disposed inclined friction faces, of a forged steel spring housing or 50 barrel, said spring housing at the open end thereof cooperating with said friction box and its closed end cooperating with one end of the friction producing spring.

In the drawings wherein I have illustrated 55 a single embodiment of the invention:

Figure 1 is a transverse longitudinal sectional view of a friction unit constructed in accordance with my invention.

Figure 2 is a similar view to Figure 1, taken however at right angles to the plane 60 of Figure 1.

Figure 3 is a rear elevation of the friction box.

Figure 4 is a front elevation of the spring housing. 65

Throughout the specification and drawings like parts are designated by like reference characters.

The numeral 1 designates a friction box, generally rectangular in outline, which is 70 provided with a pair of inwardly inclined wedging friction faces 2. At its inner end the friction box 1 is provided with a flat bearing face 3 against which the outer end of a spring housing or barrel 4 is adapted 75 to bear. The said spring housing or barrel 4 is adapted to be formed in any convenient or well known manner by a forging or pressing process from a billet. This method of so forming the barrel or spring housing is 80 possible by providing a pair of the side walls of said barrel, as will hereinafter be pointed out, arranged at an angle to the longitudinal axis of the barrel and the opposite side walls arranged parallel with said 85 axis. This formation of the spring barrel permits the use of a tapered die, there being sufficient draft formed by the angular disposition of the side walls to permit the ready withdrawal of the die after the press- 90 ing operation is completed and at the same time by arranging the angularly disposed faces in rear of the friction faces of the friction box 1 the strength of the assembled gear is greatly augmented. By forming the 95 spring barrel from a billet by a forging or pressing process all danger of defective material due to faulty castings is avoided, the weight of the friction barrel is materially lessened, and the cost thereof is maintained 100

in substantially the same figure as the corresponding cast barrel while the strength of the barrel is of course greatly superior to a cast barrel of like section. Preferably the outer end of the spring housing 4 is sub- 105 stantially the same size as the rear end of the friction box 1 whereby the respective faces of the friction box and spring hous- ing at their point of contact are in substan- tially the same planes. Adjacent the end 110

walls of the box 1 and projecting rearwardly from the face 3, I provide the said box 1 with a pair of lugs 5—5. Each of the lugs 5 is substantially U-shaped and is adapted to fit against the inside faces of the end walls 6 of the housing 4 so as to accurately center the box 1 with reference to the longitudinal axis of the housing 4. The arm portions 7 of each lug 5 are adapted to engage the side walls 8 of the spring housing 4. The outer faces of the lugs 5 preferably are beveled, as at 9, to agree with the inclination of the end walls 6 of the housing and the inner faces of the lugs 5 are also tapered, as at 10, so as to form guiding means for accurate positioning of the forward end of the outer spring 11 which is located within the spring housing 4.

Intermediate the wedging friction faces 2 I provide a plurality of friction blocks 12 and 13. The friction blocks 12 are adapted respectively to engage the faces 2 of the box 1 and the wedge 13 is interposed between the wedging friction faces 14 of the blocks 12. At its inner end the wedge 13 is seated upon the spring 11 and, if desired, there may be an additional lighter spring 15 interposed between the rear end of the housing and a recess 16 in the wedge block 13.

In order to compensate for the additional strain due to the location of the friction faces 2, I preferably thicken the end walls 6 of the housing 4 so as to strengthen the same against deflection and excessive loads imposed upon the friction mechanism, and since the walls 6 are arranged substantially parallel to the friction faces 2 the strains will be imposed thereon substantially in the plane of the wall.

It will be observed that the opening or throat 17 of the friction box is of less diameter than the diameter of the spring 11 and is also of less diameter than the outwardly flared portion 18 of the central friction block 13. By utilizing the rectangular spring housing which is preferably closed at its inner or rear end, I provide a casing which is adapted to cooperate with either a horizontal or vertical yoke without requiring supplemental guide pieces, since the forward end of the casing is of such dimension that it will exactly fit within the standard sill spacing if placed between the sills with its long axis at right angles to the plane of

the sill and which will exactly fit between the arms of a horizontal yoke if arranged with its long axis parallel to the plane of the sill.

In addition, by utilizing a rectangular spring housing or barrel I avoid abrupt change of direction between the casing and friction box and make an exceedingly slight structure which, owing to the absence of projections, cannot catch on carry irons or tie plates and thus fail to operate in its usual and intended manner.

Having thus described my invention what I now claim and desire to secure by Letters-Patent is:—

1. The combination with a hollow cast friction box having inclined friction faces formed on the inner side walls thereof, of a forged steel housing adapted to coact with said friction box, the side walls of said housing disposed immediately in rear of the said friction faces converging inwardly throughout their length toward the inner end of said housing, and means carried by said friction box for positioning the same with reference to said housing.

2. The combination with a hollow friction box having on a pair of inner side walls converging friction faces, of a pressed steel housing adapted to coact with said friction box, the side walls of said housing disposed immediately in rear of said friction faces converging inwardly throughout their length toward the inner end of said housing, said side walls being thicker in cross-section than the remaining walls of said housing.

3. The combination with a hollow rectangular friction box having on a pair of inner side walls converging friction faces, of a rectangular pressed steel housing having an open end adapted to coact with said friction box, the side walls of said housing disposed immediately in rear of said friction faces converging inwardly throughout their length toward the closed inner end of said housing, the said side walls being thicker in cross section than the remaining walls of said housing, and a spring within said housing reacting at one end against the same, the line of contact between said box and housing being in substantially the same plane.

In testimony whereof I affix my signature,
BYERS W. KADEL.
